TAPE STORAGE RACK

Robert P. McInnes, 1108 Fairway Drive,
Linden, Mich. 48451

Filed Feb. 26, 1973, Ser. No. 335,529

Term of patent 14 years

Int. Cl. D3—99

U.S. Cl. D87—1 D

FIG. 1

FIG. 2

FIG. 3

FIG. 1 is a perspective view of a tape storage rack embodying my new design;

FIG. 2 is a side elevational view; and

FIG. 3 is an enlarged, sectional view taken on the line 3—3 of FIG. 2.

The top is of uniform width throughout its length and the top and rear surfaces are plain and unornamented.

I claim:

The ornamental design of a tape storage rack, as shown.
